US00D746066S

(12) **United States Design Patent**
McCuaig

(10) **Patent No.:** **US D746,066 S**
(45) **Date of Patent:** **** Dec. 29, 2015**

(54) **FLOOR PANEL WITH FAUX STONE PATTERN**

(71) Applicant: **Armstrong World Industries, Inc.**,
Lancaster, PA (US)

(72) Inventor: **Jeannette McCuaig**, West Grove, PA
(US)

(73) Assignee: **AWI Licensing Company**, Wilmington,
DE (US)

(**) Term: **14 Years**

(21) Appl. No.: **29/480,428**

(22) Filed: **Jan. 26, 2014**

(51) **LOC (10) Cl.** **05-06**

(57) **CLAIM**

The ornamental design for a floor panel with faux stone pattern, as shown and described.

DESCRIPTION

The sole FIGURE is a plan view of a floor panel with faux stone pattern showing my new design.

The broken line perimeter surrounding the floor panel with faux stone pattern depicts the boundaries of the claim and forms no part thereof.

1 Claim, 1 Drawing Sheet
